UNITED STATES PATENT OFFICE

ARTHUR DE REPENTIGNY, OF OTTAWA, ONTARIO, CANADA, ASSIGNOR OF ONE-HALF
TO ARTHUR LA BROSSE, OF OTTAWA, ONTARIO, CANADA

AIR DISTRIBUTOR FOR PAPER-MAKING MACHINES

Application filed June 18, 1928. Serial No. 286,430, and in Canada March 16, 1928.

My invention relates to improvements in air distributors for paper making machines, and the object of the invention is to provide an improved air distributor to be used in connection with the calender rolls of paper making machines whereby the air directed against the paper passing over the rolls may be adjusted and regulated as desired so as to obtain a uniform drying effect across the extreme width of the paper and thus obtain a better finish on the paper.

My invention consists in the construction and arrangement of parts all as hereinafter more particularly described and illustrated in the accompanying drawings, in which:

Figure 1 is a diagrammatic end view showing the calender rolls of a paper machine with my improved air distributor associated therewith.

Figure 2 is a top plan view of a portion of my improved device.

Figure 3 is a transverse section on the line 3—3 of Fig. 2.

Figure 4 is a perspective view of my improved air distributor, one end thereof being broken away.

Figure 5 is a perspective view of an inner tube forming part of my improved air distributor, a portion at one end being broken away.

In the drawings like characters of reference indicate corresponding parts in the various views.

In the form illustrated, my invention consists of an improved air distributor indicated collectively by the numeral 6. This air distributor comprises an inner tube 7 provided with a longitudinal slot 8 in one side thereof. Upon the inner tube 7 are mounted a number of sleeve sections 9, which sections are independently rotatable upon the tube 7. Each sleeve section 9 is formed with a longitudinal slot 10 adapted to be brought into register with the slot 8 in the inner tube.

The sleeve sections 9 are retained upon the inner tube 7 by a collar 11 mounted upon the inner tube 7 adjacent to each end thereof.

The ends of the inner tube 7 are provided with coupling elements such as the threaded

ends 12 whereby the device may be connected to a source of air supply.

Extending longitudinally of the device and secured in position in any suitable way such as fastening to the collars 11 is a bar 13. Each sleeve section 9 carries a pin 14, which pins are so positioned that as the sleeve is rotated this pin strikes against the bar 13 when the slot 10 in the sleeve is in registration with the slot 8 of the inner tube.

These pins and the bar 13 thus constitute stop means operable to limit the rotation of the sleeves when the slots 10 are in register with the slot 8.

In operation my improved distributor is mounted adjacent to one of the calender rolls 15 of a paper making machine and is spaced slightly away from the roll and disposed parallel to the axis of the roll. The device is so mounted that the slot 8 in the inner tube is directed towards the calender roll.

The paper passing over the calender rolls is indicated by the numeral 16. The air supply to the device is connected to the coupling elements 12 at the ends of the inner tube so that when the slot 8 is uncovered air is directed against the paper passing over the roll to accomplish the desirable drying effect.

It frequently happens that to obtain a uniform drying effect across the entire width of the paper, it would be a great advantage if the air supply across the width of the paper could be adjusted and regulated as desired and this control is conveniently provided in my device since the sleeve sections 9 are independently rotatable upon the inner tube 7 so that the slot 8 in the inner tube may be closed to the passage of air entirely, or shut off as may be desired at various points across the width of the roll.

The pins 14 provide a convenient stop means for moving the various sleeve sections 9 into their open positions.

In the form illustrated diagrammatically in Fig. 1, three calender rolls are shown and one of my air distributors is associated with each roll but, of course, each distributor is independent of the others and if desired only one need be used.

From the foregoing it will be apparent that

I have devised an improved device of the class described whereby the objects of my invention have been attained. Various modifications may be made in my invention without departing from the spirit thereof or the scope of the claim, and therefore the exact form shown is to be taken as illustrative only and not in a limiting sense, and I desire that only such limitations shall be placed thereon as are imposed by the prior art or are specifically set forth in the appended claim.

What I claim as my invention is:

In a paper making machine, the combination with the calender roll thereof, of an air distributor associated therewith and positioned in spaced relation therefrom and parallel to the axis of the calender roll, said air distributor comprising an inner tube provided with a longitudinal slot directed towards the calender roll, a plurality of independently rotatable abutting sleeve sections mounted thereon, each sleeve section provided with a longitudinal slot adapted to be independently brought into registration with the slot in the inner tube, collars secured upon the inner tube and abutting the outer ends of the outermost sleeves, a bar secured to said collars and extending longitudinally of the sleeves, a pin secured to each sleeve and projecting radially therefrom, said pins adapted to engage the bar to limit the rotation of the sleeve when the slot in the sleeve registers with the slot in the inner tube, and coupling elements at the ends of the inner tube.

In witness whereof I have hereunto set my hand.

ARTHUR DE REPENTIGNY.
